UNITED STATES PATENT OFFICE

FREDERICK W. BRIXNER, OF ROCHESTER, NEW YORK, ASSIGNOR TO GENERAL RAILWAY SIGNAL COMPANY, OF ROCHESTER, NEW YORK

TRAIN DISPATCHING SYSTEM FOR RAILROADS

Application filed November 25, 1929. Serial No. 409,663.

This invention relates to train dispatching systems of the wayside signal indicating type, and more particularly to a synchronous selector system employing distinctive code impulses for rendering available specific message circuits.

When it is desired to direct the movement of trains on a railway system, and control the switch machines for the track switches over which such train is to move, it is of course expedient to employ a system having the fewest possible line wires, in that the control mentioned may extend over a distance of more than one hundred 15 miles, and it is only economical if the number of line wires are reduced to a small value.

In accordance with the present invention it is proposed to employ a single line circuit, 20 which is at times used for actuating code responsive devices to set up message circuit branches, and is at other times used to transmit control or indication messages thereover, and through the message circuit branches so completed. In other words, the single line circuit mentioned is at times used as a channel selecting circuit and is at other times used as a message circuit.

Other objects, purposes and characteristic 25 features of the invention will in part be obvious from the accompanying drawings, showing one specific embodiment of the present invention, and will in part be pointed out in the specification hereinafter.

In describing the invention in detail reference will be made to the accompanying drawings in which:—

Fig. 1A conventionally illustrates a portion 40 of the apparatus in the dispatcher's office, of one embodiment of the present invention; and

Fig. 1B illustrates conventionally the apparatus of the same embodiment at a distant way station of the railway system.

The drawings if laid end to end illustrate 45 a portion of the entire system.

Structure

Referring to Fig. 1B, although the invention, in practice, is applied to a large num-

ber of track switches, passing sidings, railway crossings, and the like, for convenience the invention has been shown applied only to a way station constituting the end of a passing siding PS. The rails 10 have been 55 shown divided by insulating joints 11, to constitute the usual insulated detector track circuit including the track relay TR and the track battery 12, for protecting trains approaching the track switch S¹ at the west 60 end of this passing siding PS. The entrance of trains into the passing siding PS is governed by the main entering signal 8S and the take-siding signal 8DS, whereas the departure of trains from the main track 65 and the side track into the single track section N, is governed by the main starting signal 7S and the dwarf starting signal 7DS. The track switch S¹ is preferably 70 operated by a switch machine SM, which switch machine in turn is controlled by the switch machine relay SMR, which relay in turn is controlled by the synchronous selector system, more particularly described hereinafter.

In practice the railway system is preferably reproduced in the dispatcher's office in miniature, and for convenience the west end of the passing siding PS has only been reproduced in miniature in Fig. 1A of the 80 drawings by the track lay-out constituting the left hand portion only of the miniature passing siding ps. With the left hand end of this miniature passing siding ps is associated the signal lever LS for controlling the signals at the west end of the passing siding PS, and a switch machine lever LSM used for the purpose of controlling the switch machine SM at the distant passing siding PS. There is also provided an indicating 85 lamp I at the west end of the passing siding ps, which is controlled by the indicating relay IR, which relay in turn is controlled through the synchronous selector system and indicates whether or not the track relay TR 90 of the distant passing siding PS is energized, so that the illumination of the lamp I indicates occupancy of the detector track circuit illustrated in Fig. 1B.

Let us now consider the apparatus in- 100

volved in the synchronous selector system, over which the control and indication impulses, heretofore mentioned, are transmitted. In accordance with the present invention there is only one line circuit, including a "selecting and message" wire 15 and a "common return" wire 16. In the dispatcher's office there is a suitable source of alternating current AC, preferably of commercial frequency, such as 60 cycle, and a storage battery 20, preferably having its midpoint connected to the common wire 16 through the medium of wires 17 and 18. In the dispatcher's office there is a motor generator set, comprising a direct current generator G, an alternating current motor F^{60} , and distinctive frequency generators F^1 , F^2 , F^3 and F^n . The motor F^{60} is normally driven by current derived from the source AC, and the generator G normally charges the storage battery 20, but in case of power failure the generator G acts as a motor to drive the generators F^1 , F^2 , F^3 and F^n . This motor generator set drives, through the medium of reduction gearing RG, a suitable commutator or circuit selector 22, which for convenience has been shown developed, so as to more clearly illustrate the segments by which certain circuits are completed and the arc of movement through which they are completed.

The dispatcher's office equipment also includes filters FL^1 , FL^2 , FL^3 and FL^n , of which each filter is so designed as to allow current of a particular frequency, these frequencies being distinguished by the exponents of the reference characters of such filters, to flow freely, whereas such filter greatly restricts the flow of currents of all other frequencies. Each of these filters is connected in series with the generator of the corresponding frequency, so that all of these generators can simultaneously supply alternating current to the primary winding of the transformer T without the flow of cross currents between generators.

At the distant way station (see Fig. 1B) there is preferably provided a similar transformer T^1 upon which the frequencies delivered by the transformer T are impressed, at least when this transformer T is connected to the selecting and message wire 15. This transformer T^1 has a condenser C connected in series therewith, so as to prevent the flow of direct current through the transformer T^1 , for reasons which will appear hereinafter. The transformer T^1 has its secondary winding connected across a multiple frequency bus, which bus in turn is connected to similar filter WFL^1 , WFL^2 , WFL^3 and WFL^n , each filter of which permits the flow of current of a frequency corresponding to that of the exponent of its reference character to a rectifier of the double wave type, which in turn delivers direct current to a quick act-

ing direct current relay, these relays being designated R^n , R^1 , R^2 and R^3 , respectively. The relays R^1 , R^2 and R^3 in turn control repeater relays RR^1 , RR^2 and RR^3 . There is also provided a repeater relay RR^{12} , which can only pick up in the event that the relays R^1 and R^2 have picked up before the relay R^3 has picked up, these various distinctive frequency relays and repeater relays in turn control a large number, six in the particular arrangement illustrated message circuit branches, each branch of which includes the message relay MR and a suitable control relay or control device, depending upon whether it controls, or is controlled by apparatus at that way station.

These message circuit branches when closed synchronously with corresponding message circuit branches closed in the dispatcher's office by the commutator 22, may control the switch machine relay SMR, the signal relay SR, the direction relay DR, and the indicating relay IR (see Fig. 1A) respectively, in response to the condition of the switch machine lever LSM, the signal control lever LS and the condition of energization of the track relay TR. Having now briefly pointed out the various elements of a system constituting one embodiment of the present invention, it is deemed expedient to consider the operation of this system, so that the coordination of the various elements thereof are more clearly understood.

Operation

Let us assume that there is an east-bound train moving in the single track section N, and that the dispatcher, located in the dispatcher's office (see Fig. 1A) wishes this train to take the side track of the passing siding PS. In order to accomplish this, it is necessary that the track switch S^1 be operated to the take-siding position. The dispatcher in order to so operate the track switch S^1 will move his lever LSM to the left hand dotted position. The commutator 22, in the present form of the invention is presumably rotating at all times, and let us now observe what transpires as this commutator 22 rotates with the lever LSM in the left hand dotted position, and with the lever LS in the right hand position, because the dispatcher wishes to set up indications for east-bound movement over the track switch S^1 .

Message circuit one

Rotation of the commutator 22 in the direction of the arrow causes the segments 24 and 25 to simultaneously engage the stationary brushes 1 and 26. The short circuiting of the first two of the brushes 1, connects the transformer T to the selecting and message wire 15, and the short circuiting of brushes 26 applies frequency F^1 across the wires 15 and 16 through the medium of this trans-

former T. This application of frequency F^1 to the line circuit 15—16 causes current of frequency F^1 to flow through the filter WFL¹ (see Fig. 1B), through rectifier RT¹ and to the relay R¹. With the relay R¹ energized the following pick up circuit is closed for the repeater relay RR¹—beginning at the plus terminal of the battery 30, wires 27, 28 and 29, front contact 31 of the relay R¹, wires 32, 33 and 34, back contact 35 of the relay R², wires 36 and 37, upper winding of the relay RR¹, to the minus terminal of the battery 30. No message circuit is completed by the picking up of the relays R¹ and RR¹.

After another short arc of rotation of the commutator 22, the commutator segment 40 engages the stationary contact brushes 41, thereby effecting the application of frequency F^2 to the transformer T, and in turn to the synchronous selector circuit 15—16, the transformer T¹, the filter WFL², the rectifier RT² and to the relay R². This of course will effect energization of the relay R², but this relay R² cannot pick up the repeater relay RR², because the pick up circuit for the repeater relay RR² is open at the back contact 31 of the relay R¹. This picking up of the relay R² will, however, close a pick-up circuit for the repeater relay RR¹², through a pick-up circuit which may be traced as follows:—beginning at the plus terminal of the battery 30, wires 27, 42 and 43, back contact 44 of the relay R¹, wire 45, front contact 46 of the relay R¹, wire 47, front contact 48 of the relay R², wire 49, back contact 50 of the relay R³, wires 51 and 52, to the upper winding of relay RR¹².

With the relay RR¹² picked up, and the relay R¹ up and relay RR² down, as is now the case, the following stick circuit for the upper winding of the relay RR¹² is completed:—beginning at the plus terminal of the battery 30, wires 27, 28 and 29, front contact 31 of the relay R¹, wires 32 and 55, back contact 56 of the relay RR², wires 57 and 58, front stick contact 59 of the relay RR¹², wires 60 and 52, through the upper winding of the relay RR¹², to the negative terminal of battery 30.

Continued rotation of the commutator 22 causes engagement of the segments 62 and 63 with their respective stationary contact brushes 64 and 65. This causes the simultaneous application of frequencies F^3 and F^n to the selecting circuit 15—16. The frequency F^n , although it can reach the filter WFLⁿ and the rectifier RTⁿ, cannot flow to the upper winding of the relay Rⁿ until the relays R¹, R² and R³ have all assumed their energized positions. The flow of frequency F^3 , through the relay R³, through the medium of filter WLF³ and rectifier RT³ will, however, effect picking up of the relay R³, so that frequency F^n can reach the relay Rⁿ after having its current rectified, so that the

relay Rⁿ also picks up. Picking up of the relay R³ cannot effect picking up of its repeater relay RR³, because the back contacts 67 and 46 of the relays R² and R¹ included in the pick-up circuit for the relay RR³ are open. It is thus seen that the application of frequencies F^1 , F^2 and F^3 , in the order given, followed by the application of frequency F^n has caused the relays R¹, RR¹, R², RR¹², R³ and Rⁿ, and with these relays all up, each one of the repeater relays will be stuck up. The relay Rⁿ and the repeater relays RR¹ and RR¹² will be stuck up through the following respective stick circuits:—

(1) Beginning at the plus terminal of the battery 30, wires 27, 42 and 70, back contact 71 of the message relay MR, wire 72, stick contact 73 of the relay Rⁿ, wire 74, lower winding of the relay Rⁿ, to the negative terminal of the battery 30; 80

(2) Beginning at the plus terminal of the battery 30, wires 27, 42 and 43, front contact 44 of the relay Rⁿ, wires 75, 76 and 77, front stick contact 78 of the relay RR¹, wire 79, bottom winding of the relay RR¹, to the negative terminal of the battery 30; and 90

(3) Beginning at the positive terminal of the battery 30, wires 27, 42 and 43, front contact 44 of the relay Rⁿ, wires 75, 76, 80 and 81, front stick contact 82 of the relay RR¹², wire 83, bottom winding of the relay RR¹², to the negative terminal of the battery 30. 95

Continued rotation of the commutator 22 cuts off all of the frequencies F^1 , F^2 , F^3 and F^n but the relays Rⁿ, RR¹, RR¹² nevertheless remain energized, through the stick circuits just traced. Also, the disengagement of commutator segment 24 with the first two brushes 1 will disconnect the transformer T 100 from the selecting line 15, and a slight further rotation of the commutator 22 causes the contact segment 85 to engage the second two brushes 1, thereby connecting the switch machine lever LSM to the selecting and message wire 15, which results in the closing of the following message circuit connecting the switch machine lever LSM and the switch machine relay SMR:—beginning at the negative terminal of the battery 20 (see Fig. 1A), wires 86, 87, 88 and 89, lever contact LSM, wire 90, contact 1, segment 85, contact 1, wire 92, front contact 93 of the relay LSMR, wires 94 and 95, message wire 15, wires 96 and 97, message relay MR, wire 98, front contact 99 of the relay Rⁿ, wire 100, back contact 101 of the relay R¹, wire 102, back contact 103 of the relay R², wire 104, back contact 105 of the relay R³, wire 106, front contact 107 of the relay RR¹, wire 108, back contact 109 of the relay RR³, wire 110, front contact 111 of the relay RR¹², wire 112, winding of the switch machine relay SMR, wires 113, 114, 115, 116, 117 and 118, line wires 16, wires 18 and 17 to the midpoint 115

120

125

130

135

of the battery 20 in the dispatcher's office. It is noted that this direct current cannot flow through the transformer by reason of the blocking condenser C.

- 5 The flow of current of negative potential in the message circuit just traced, operates the switch machine relay SMR to its left hand dotted position, which in turn effects operation of the switch machine SM to operate the switch S¹ to the take-siding position. Also, flow of current in this circuit effects energization of the message relay MR, and opening of back contact 71 of this relay MR. This opening of the back contact 71
 10 15 effects opening of the stick circuit for the relay R^a, the dropping of which in turn opens the stick circuits for the relays RR¹ and RR¹² heretofore traced. The dropping of these relays R^a, RR¹ and RR¹² of course
 20 again opens the message circuit just traced, thereby effecting deenergization of the message relay MR. The message relay MR in practice is constructed to be sufficiently slow acting to allow operation of the relay SMR
 25 before its circuit is opened at contact 99.

Message circuit two

It is of course understood that the commutator 22 continues its rotation, and after
 30 a further small arc of rotation the commutator segments 120 and 121 will engage their respective contacts 41 and 2. The segment 121 merely connects the transformer T to the stepping and message wire 15. The segment 120 short circuits the brushes 41, thereby connecting frequency F² to the transformer T and in turn to the transformer T¹ located at the distant way station. This flow of current of frequency F² effects energization
 35 40 of the relay R², thereby causing the relay RR² to be picked up through the following pick-up circuit:—beginning at the plus terminal of battery 30, wires 27, 28 and 123, front contact 35 of the relay R², wires
 45 50 55 34, 33 and 32, back contact 31 of the relay R¹, wires 124 and 125, upper winding of the relay RR², back to the negative terminal of the battery 30. With this relay RR² assuming its energized position the following stick circuit for this relay is closed:—beginning at the plus terminal of the battery 30, wires 27, 28 and 123, front contact 35 of the relay R², wires 34 and 126, back contact 127 of the relay RR¹, wires 128 and
 60 65 70 75 77, front stick contact 56 of the relay RR², wires 129 and 125, through the upper winding of the relay RR² to the negative terminal of battery 30.

After another short arc of movement of
 60 the commutator 22, the commutator segment 130 engages the brushes 26, thereby applying current of frequencies F¹ to the stepping and message circuit, and effecting energization of the relay R¹ at the way station.
 65 With the relay R¹ moved to its attracted

position after the relay RR² has assumed its attracted position, the repeater relay RR¹ cannot be energized, for reasons heretofore pointed out, but the relay RR¹² can, and will be energized through the following circuit:—beginning at the positive terminal of the battery 30, wires 27, 42 and 43, back contact 44 of the relay R^a, wire 45, front contact 46 of the relay R¹, wire 47, front contact 48 of the relay R², wire 49, back contact 50 of the relay R³, wires 51 and 52, through the upper winding of the relay RR¹², to the negative terminal of the battery 30. With the relay RR¹² picked up, it is stuck up through the following stick circuit:—beginning at the positive terminal of the battery 30, wires 27, 28 and 123, front contact 35 of the relay R², wires 34 and 126, back contact 127 of the relay RR¹, wires 128 and 58, front stick contact 59 of the relay RR¹², wires 60 and 52, through the upper winding of the relay RR¹², to the negative terminal of battery 30.

After another small arc of rotation of the commutator 22, the commutator segments 135 and 136 will engage the respective pairs of brushes 64 and 65, and thereby affect the application of frequencies F³ and F⁴ to the selecting and message circuit 15. This application of frequency F³ to the relay R³ will effect picking up of this relay R³, thereby closing its contact 66 to complete a circuit through the upper winding of the relay R^a for the flow of rectified current derived from the filter WFL^a, which circuit includes the contacts 66, 68 and 69 of the relays R^a, R² and R¹, respectively. The closure of the circuit for the upper winding for the relay R^a at a time when frequency F³ is applied to the selecting and message circuit 15—16 causes the relay R^a to assume its attracted position, thereby closing the stick circuit for the lower winding of the relay RR¹² heretofore traced, and also closing the following stick circuit for the lower winding of the relay RR²:—beginning at the positive terminal of the battery 30, wires 27, 42 and 43, front contact 44 of the relay R^a, wires 75 and 137, front stick contact 138 of the relay RR², wire 139, lower winding of the relay RR², to the negative terminal of the battery 30. The picking up of the relay R^a of course also effects closure of its stick circuit including its stick contact 73.

Another small arc of movement of the commutator 22 causes the various segments 130, 120, 135, 136 and 121 to disengage their respective stationary brushes, thereby effecting deenergization of the relays R¹, R² and R³. The relays R^a, RR² and RR¹² will however, remain in their energized position, because these relays are stuck up through stick circuits which are not broken by deenergization of the relays R¹, R² and R³. A little further movement of the commuta- 120

tor 22 causes the commutator segment 140 to engage the two right hand brushes 2, thereby completing a message circuit which, although it has not been made use of in the 5 particular embodiment of the invention illustrated, may be traced from the brush 2 as follows:—beginning at the brush 2, commutator segment 140, brush 2, wires 141 and 95, stepping and message wire 15, wires 96 and 97, message relay MR, wire 98, front contact 99 of the relay R^a, wire 100, back contact 101 of the relay R¹, wire 102, back contact 103 of the relay R², wire 104, back contact 105 of the relay R³, wires 106 and 144, front contact 145 of the relay RR², wire 146, back contact 147 of the relay RR³, wire 148, front contact 149 of the relay RR¹² to wire 150 (this wire 150 passes through a suitable control relay, not shown). The 20 flow of current through this message circuit, which is used in practice, effects energization of the message relay MR, and in turn effects deenergization of the relays R^a, RR² and RR¹², for reasons heretofore pointed 25 out.

Message circuit three

Another small arc of movement of the commutator 22 effects disengagement of segment 30 140 and its brush 2, and a further small arc of movement causes the commutator segments 155 and 156 to engage their respective stationary brushes 26 and 3. The engagement of segment 156 with brushes 3 connects 35 transformer T to the line wire 15, and the engagement of segment 155 with the brushes 26 effects the application of frequency F¹ to the distant way station apparatus, thereby effecting energization of the relay R¹. Energization of the relay R¹, by the closure of 40 its front contact 31, causes the repeater relay RR¹ to be picked up through a circuit heretofore traced, after which this repeater relay is stuck up through its stick contact 45 127 through a stick circuit heretofore traced. A slight further arc of movement of the commutator 22 causes the commutator segment 157 to engage to stationary brushes 64, thereby effecting the application 50 of frequency F³ to the selecting and message wire 15, and thereby effecting energization of the relay R³. Since the picking up of the relay R³ is preceded by the picking up of the relay R¹ the repeater 55 relay RR³ cannot be picked up, this because its pick-up circuit is broken at the back contact 46 of the relay R¹. Attention is at this time directed to the fact that picking up of the relay R³ has opened its contact 50, so that the relay RR¹² cannot be picked up in response to picking up of the relay R².

After a further short arc of movement of the commutator 22 the contacts 158 and 159 65 engage their respective stationary brushes

41 and 65, and thereby effect the application of frequencies F² and F^a to the stepping and message circuit 15—16. The frequency F^a cannot reach the relay R^a until the relay R² has been picked up and has closed 70 its front contacts 68. The relay R² will thus pick up and in turn effect the picking up of the relay R^a. The picking up of the relay R² cannot pick up the repeater relay RR², because its pick-up circuit is opened 75 at the back contact 31 of the relay R¹. With the relay R^a picked up its stick circuit will be closed including the back contact 71 of the relay MR, as well as will be the stick circuit for the relay RR¹ including its stick 80 contact 78 and the front contact 44 of the relay R^a.

A slight further arc of movement of the commutator 22, will remove the frequencies F¹, F², F³ and F^a, thereby effecting deenergization of the relays R¹, R² and R³, but the relays RR¹ and R^a will remain energized. After a further small arc of movement of the commutator 22, the commutator segment 160 will engage the two right hand brushes 3, thereby closing a message circuit which may be traced as follows:—beginning at the positive terminal of the battery 95 161, front contact 162 of the track relay TR, wire 163, back contact 111 of the relay RR¹², wire 110, back contact 109 of the relay RR³, wire 108, front contact 107 of the relay RR¹, wire 106, back contact 105 of the relay R³, wire 104, back contact 103 of the relay R², wire 102, back contact 101 of the relay R¹, wire 100, front contact 99 of the relay R^a, wires 98, winding of the message relay MR, wires 97 and 96, stepping and message wire 15, wires 95, 141 and 164, brush 3, commutator segment 160, wire 165, winding of the indicating relay IR, to the common return wire 16 connected through the medium of wires 118, 117 and 166 to the midpoint of the battery 161.

It is desired to point out at this time that if the east-bound train in question has already advanced to a point where it treads upon the detector track circuit including the track relay TR, this track relay TR will be deenergized, and will have effected the application of current of negative polarity instead of current of positive polarity to the message circuit just traced, and will have caused the indicating relay IR to be moved toward the left to effect illumination of indicating lamp I. The message circuit just traced through which control of indicating relay IR is effected, will of course be opened by the dropping of stick relays RR¹ and R^a 115 in response to lifting of the contact 71 of the message relay MR.

After a further arc of movement of the commutator 22 the segment 160 will again remove the shunt off of the brushes 33, there- 130

by opening the message circuit at the dispatcher's office.

Message circuit four

- 5 Continued movement of the commutator 22 will next cause the commutator segments 170 and 171 to engage their respective stationary brushes 41 and 4. The segment 171 connects the transformer T to the selecting and message circuit, and the segment 170 applies current of frequency F^2 to the selecting and message circuit 15—16. The application of frequency F^2 to the message circuit, and in turn to the relay R^2 at the way station, causes the relay R^2 to pick-up, and in turn closes a pick-up circuit for the repeater relay RR^2 , which pick-up circuit has already been traced hereinbefore. After the repeater relay RR^2 has been picked up it is stuck up through a stick circuit, also traced in the foregoing description and including the stick contact 56. Further movement of the commutator 22 causes the commutator segment 172 to engage the stationary brushes 64, thereby applying frequency F^3 to the stepping and message circuit and in turn to the relay R^3 , and this application of frequency F^3 to the relay R^3 causes this relay R^3 to pick up, but produces no further results in that the repeater relay RR^3 cannot be picked up, its pick-up circuit being broken at the back contact 67 of the relay R^2 . After a further short arc of movement of the commutator 22 the segments 173 and 174 will bridge their respective brushes 26 and 65, and will effect the application of frequencies F^1 and F^n . The application of frequency F^1 will cause the relay R^1 to pick up, thereby closing all of its front contacts, but will not cause the repeater relay RR^1 to pick up, because the pick-up circuit for this repeater relay RR^1 is broken at the back contact 35 of the relay R^2 . The picking up of the relay R^1 will, however, close the circuit for the upper coil of the relay R^n , so that this relay R^n can and will pick up in response to the frequency F^n which frequency has been transmitted to the way station. With the relay R^n picked up the stick circuit, heretofore traced, for its own lower winding as well as the stick circuit for the lower winding of the relay RR^2 , is completed. A slight further arc of rotation of the commutator 22 causes the frequencies F^1 , F^2 , F^3 and F^n to be cut off of the selecting and message circuit, so that the relays R^1 , R^2 and R^3 return to their retracted position, but the relays R^n and RR^2 will remain energized, so that the following message circuit is completed as soon as the commutator segment 175 engages the two right hand brushes 4 in the dispatcher's office:—beginning at the plus terminal of the battery 20, (see Fig. 1A), wires 176, 177, 178, 179 and 180, lever contact LS assuming its right hand position, wire 181, brush 4, commutator segment 175, brush 4, wires 182 and 183, front contact 184 of relay LSR, wires 84, 94 and 95, stepping and message wire 15, wires 96 and 97, winding of the message relay MR, wire 98, front contact 99 of the relay R^n , wire 100, back contact 101 of the relay R^1 , wire 102, back contact 103 of the relay R^2 , wire 104, back contact 105 of the relay R^3 , wires 106 and 144, front contact 145 of the relay RR^2 , wire 146, back contact 147 of the relay RR^3 , wire 148, back contact 149 of the relay RR^1 , wire 185, the direction relay DR, wires 186, 115, 116, 117 and 118, common return wire 16, wires 18 and 17, and back to the midpoint of battery 20. The flow of current of positive polarity through the direction relay DR will not change the position of this relay, but with this relay DR in the right hand normal position east-bound signals only can be cleared, and as soon as the signal relay SR assumes its right hand position the east-bound take siding signal 8DS will assume its proceed position, providing traffic conditions in advance are cleared and this will indicate to the approaching train that it may enter the side track of the passing siding PS. The flow of current through the last message circuit traced, including the direction relay DR, will of course also flow through the message relay MR. The lifting of contact 71 of relay MR will of course open the stick circuits for the relays R^n and RR^2 , so that these stick relays will again assume their retracted position.

Message circuit five

Further movement of the commutator 22 causes the segment 175 to disengage its stationary brushes 4, and causes the segments 190 and 191 of the commutator 22 to engage their respective brushes 64 and 5. The engagement of brushes 5 by segment 191 re-connects the transformer T to this selecting and message circuit 15, and engagement of commutator segment 190 with its brushes 64 effects the application of frequency F^3 to the selecting and message circuit 15. The flow of this frequency F^3 to the distant way stations finds its way to the relay R^3 through the medium of the filter WFL^3 and the rectifier RT^3 , thereby effecting energization of the relay R^3 . With the relay R^3 energized the following pick-up circuit for the upper winding of the repeater relay RR^3 is closed:—beginning at the positive terminal of the battery 30, wires 27, 42 and 43, back contact 44 of the relay R^n , wire 45, back contact 46 of the relay R^1 , wire 192, back contact 67 of the relay R^2 , wire 193, front contact 194 of the relay R^3 , wires 195 and 196, upper winding of the relay RR^3 to the negative terminal of battery 30. With the relay RR^3 energized through the

medium of the circuit just traced, the following stick circuit for the upper winding of this relay RR^3 is closed:—beginning at the positive terminal of the battery 30, wires 27 and 197, front contact 198 of the relay R^3 , wire 199, front stick contact 200 of the relay RR^3 , wires 201 and 196 to the upper winding of the relay RR^3 .

A further small arc of movement of the commutator 22 causes the commutator segment 205 to engage its brushes 26, and effect the application of current of frequency F^1 to the selecting and message circuit, which in turn effects picking up of the relay R^1 . The picking up of the relay R^1 , causes the pick-up circuit for the repeater relay RR^1 , heretofore traced, to be closed, thereby effecting picking up of the relay RR^1 and in turn effecting closure of the stick circuit of the upper winding for the relay RR^1 , which stick circuit has been traced hereinbefore. This picking up of the relay R^1 cannot pick up the relay RR^{12} , because the back contact 50 of relay R^3 and front contact 48, both of which are open, are included in the pick-up circuit for the relay RR^{12} .

A slight further rotation of the commutator 22 causes the commutator segments 206 and 207 to engage their respective stationary brushes 41 and 65, which of course causes currents of frequencies F^2 and F^n to be transmitted to the distant way station. The flow of frequency F^2 causes the relay R^2 to pick up, thereby closing the circuit through the upper winding of the relay R^n to permit the flow of frequency F^n to said winding. The picking up of relay R^2 will not effect picking up of the relay RR^{12} because the pick-up circuit of said relay is open at the back contact 31 of the relay R^1 , and will not effect picking up of the relay RR^{12} because the pick-up circuit for said relay RR^{12} is open at the back contact 50 of the relay RR^3 . Under the conditions under consideration the relays R^3 , RR^3 , R^1 , RR^1 , R^2 and R^n are thus energized, and with the relay R^n energized the stick circuits for the bottom windings of the relays R^n , RR^1 and RR^3 are closed, so that movement of the commutator 22 to a position to disengage the segments 205, 206, 190, 207 and 191 from their respective brushes will effect deenergization of the relays R^1 , R^2 and R^3 , but will leave the relays R^n , RR^1 and RR^3 energized, so that the following message circuit is closed as soon as the commutator segment 209 engages the two right hand brushes 5 of the commutating equipment. This message circuit may be traced as follows:—beginning at the positive terminal of the battery 20, wires 176, 177, 178, 210 and 211, contact 212 of the lever LS in its right hand position, wire 213, brush 5, commutator seg-

ment 209, brush 5, wires 214 and 183, front contact 184 of relay LSR, wires 84, 94 and 95, selecting and message wire 15, wires 96 and 97, winding of the message relay MR, wire 98, front contact 99 of the relay R^n , wire 100, back contact 101 of the relay R^1 , wire 102, back contact 103 of the relay R^2 , wire 104, back contact 105 of the relay R^3 , wire 106, front contact 107 of the relay RR^1 , wire 108, front contact 109 of the relay RR^3 , wire 215, winding of the signal relay SR, wires 216, 114, 115, 116, 117 and 118, common return wire 16, wires 18 and 17, back to the midpoint of the battery 20. The flow of current of positive polarity in the message circuit just traced, will of course operate the signal relay SR to its right hand position, thereby causing the take-siding signal 8DS to be cleared, assuming traffic conditions in advance to be favorable, so that the east-bound train approaching in the single track section N may move into the side track of the passing siding PS. The movement of this train into the side track, will of course effect deenergization of the track relay TR and will effect operation of the indicating relay IR (see Fig. 1A) to its left hand position during the next cycle of operation of the commutator 22, and will thereby effect illumination of the associated indicating lamp I. The flow of current in the message circuit just traced will of course effect momentary energization of the message relay MR, and will thereby cause the stick circuits for the relays RR^1 , RR^3 and R^n to be broken to allow these relays to again move to their retracted position. Also, continued movement of the commutator 22 causes this message circuit to be broken at the dispatcher's office at the commutator segment 209.

Message circuit six

Continued movement of the commutator 22 causes the commutator segments 220 and 221 to engage their respective stationary brushes 64 and 6. The engagement of brushes 6 by segment 221 will reconnect the transformer T to the selecting and message circuit 15—16. The engagement of brushes 64 by the segment 220 causes frequency F^3 to be reapplied to the selecting and message circuit 15—16, and the application of this current of frequency F^3 will cause the relay R^3 to assume its attracted position, thereby picking up the repeater relay RR^3 through the pick-up circuit heretofore traced. Further rotation of the commutator 22 causes the commutator segment 222 to engage its stationary contacts 41, thereby causing frequency F^2 to be transmitted to the distant way station. The flow of this frequency F^2 to the distant way station causes the relay R^2 , and in turn the repeater relay RR^2 to assume their energized position, for rea-

sons heretofore given. Another small arc of rotation of the commutator 22 causes the commutator segments 223 and 224 to engage their respective brushes 26 and 65. The engagement of segment 223 with its brushes 26 causes current of frequency F^1 to flow to the distant relay R^1 . Picking up of the relay R^1 will however, not effect picking up of the repeater relay RR^1 , for reasons here-
tofore given, it will, however, effect the closure of its front contact 69 and allow the frequency F^n to reach the upper winding of the relay R^n . With the relay R^n energized, its own stick circuit as well as the stick circuits for the relays RR^2 and RR^3 will be closed, so that the removal of the frequency F^1 , F^2 , F^3 and F^n by reason of rotation of the commutator 22 to a position where the segment 223, 222, 220, 224 and 221 disengage
their respective brushes will leave the relays RR^2 , RR^3 and R^n in their attracted position. A slight further arc of movement of the commutator 22 causes the commutator segment 225 to engage the two right hand brushes 6, thereby completing a message circuit starting at the wire 226, which message circuit has not been shown connected to control electro responsive devices:—beginning at the wire 226, brush 6, segment 225, brush 6, wires 230, 164, 141 and 95, selecting and message wire 15, wires 96 and 97, winding of the message relay MR, wire 98, front contact 99 of the relay R^n , wire 100, back contact 101 of relay R^1 , wire 102, back contact 103 of relay R^2 , wire 104, back contact 105 of relay R^3 , wires 106 and 144, front contact 145 of relay RR^2 , wire 146, front contact 147 of relay RR^3 , to suitable control or controlled apparatus.

40 Summary

Having now described a small portion of a dispatching system embodying the present invention, let us consider how this portion may be expanded into a system having many way stations and associated apparatus. Referring to the drawings, and especially to the commutator its segments for applying frequency F^n , it will be noted that frequency F^n is always applied as the last frequency of the group of frequencies applied in a particular order. Also, referring to Fig. 1B, it will be noted that the frequency F^n cannot reach its relay R^n until all three of the relays R^1 , R^2 and R^3 assume their energized position. Also, attention is directed to the fact that the relay R^n when once picked up is stuck up until a message current has passed through the message relay MR and has interrupted the stick circuit of the relay R^n including the contact 71 of the message relay MR. In this connection, it is desired to point out that in practice the various control relays which are controlled through message circuits are

somewhat quicker acting than is the message relay MR, so that it is assured that these control relays will have responded to the message current before the message channel has been interrupted by reason of dropping of the relay R^n . Also, in practice for every message channel for which a particular code of distinctive impulses is necessary, will not have such distinctive code of impulses transmitted, unless that particular message circuit is actually connected up, for otherwise the system would become locked up in that the message relay MR could not be momentarily energized to restore the stick relays stuck up through the back contact 71 of this relay MR. If a particular message circuit is left over, and can not be made use of, a source of current and a resistance unit may be included therein solely for the purpose of effecting momentary energization of the message relay MR.

The frequency F^n may therefore be called a retaining frequency, and is a frequency that is used at each end of every way station. The frequencies F^1 , F^2 and F^3 may be considered as selecting frequencies, the order in which these frequencies being applied determining the particular message circuit branch at a particular way station that shall be closed.

Let us now consider how the system may be expanded by using other distinctive frequencies such as F^4 and F^5 (no apparatus having been shown for generating these frequencies). It readily appears that if one additional frequency is used such as a frequency F^4 , that four way stations each having six message channels may be controlled, assuming that groups of three distinctive selecting frequencies are used. For instance, the first way station, as shown, would employ the frequencies F^1 , F^2 and F^3 , the second way station (see way station #2, Fig. 1B), for instance, might use the frequencies F^1 , F^2 and F^4 . The third way station, might, for instance, use the frequencies F^1 , F^3 and F^4 , whereas the fourth way station could use the remaining combination of frequencies F^2 , F^3 and F^4 , so that four way stations exactly constructed as the way station shown in Fig. 1B, except that different combinations of filters are used, may be controlled by four distinctive selecting frequencies. If, on the other hand, five distinctive selecting frequencies are used, ten different combinations, using three frequencies at a time, may be taken advantage of, so that ten different way stations could be controlled by the employment of five distinctive selecting frequencies to which the frequency F^n would of course have to be added to determine the total number of distinctive frequencies used.

It is now desired to direct attention to the manner in which the selecting and mes-

sage circuit 15-16 is first used as a selecting circuit and is then used as a message circuit. It will be noted that when the various distinctive frequencies are applied 5 to the selecting circuit 15-16, that a certain commutator segment, such as the commutator segment 24, connects the transformer T to the stepping and message circuit, and that this connection is again interrupted as 10 soon as the selecting function has been completed, while another commutator segment such as the segment 85 connects a particular message circuit branch to the selector wire 15, so that first one type of apparatus, 15 namely the selecting apparatus is connected at the dispatcher's office, and that at another time the control and indication apparatus at the dispatcher's office is connected to the selector and message circuit 15-16. 20 Also, at the way station shown no message circuit can be connected until all of the selecting relays R¹, R², R³ and R^a have assumed their energized position, the relay R^a is stuck up and the relays R¹, R² and R³ 25 have been deenergized by reason of removal of the corresponding frequencies. Further, the direct current which is used in the message circuit cannot reach the transformer T¹ by reason of the inclusion of the condenser C in series with the primary winding of this transformer T¹, so that the way station apparatus has its various control relays and its track relay contacts connected to the message circuit 15-16 only, after the selecting 30 function has been completed. In this connection, should a code of distinctive frequencies be transmitted, including say the frequencies F¹ and F² but not including the frequency F³, the code in question being intended for a way-station other than the one shown in Fig. 1B, even though the relay RR¹ would in this case be picked up and stuck up providing this frequency F¹ was the first frequency to be transmitted, this 35 relay RR¹ could for reasons heretofore given not complete a message circuit and would be again dropped as soon as the frequency F¹ were removed from the selecting circuit, and this would happen as soon as the entire 40 code has been transmitted. In other words, the circuit organization is such that the transmission of a partial code only cannot set up a message circuit branch, and such contacts as are closed will again be opened as soon 45 as the entire code has been transmitted or as soon as all frequencies are removed from the selecting circuit.

It will be noted that the selecting circuits for setting up message circuits four and 50 five are carried through wire 183 (see Fig. 1A) through the front contact 184 of the relay LSR, and that the selecting circuit for establishing message circuits one is carried through the front contact 93 of relay LSMR. 55 In other words, the codes of particular fre-

quencies applied in a particular order for a particular message circuit are not transmitted unless the lever contact included in such message circuit is closed, this result being accomplished by the relays LSR and LSMR. 60 There are two distinct advantages afforded by the relays LSR and LSMR, namely, (1) by the provision of these relays certain distinctive codes are not transmitted when the corresponding levers assume the neutral position, so that the particular distinctive frequency relays at the distant way stations are not operated and thus save energy and wear and tear on these relays, and (2) if the distinctive code to complete a particular message circuit were transmitted, and no message were transmitted over the message circuit completed by such distinctive code, the message relay MR at such particular way-station would not be energized and the message circuit would remain established, which of course would be undesirable. 75

Having thus shown and described only a portion of a dispatching system, and having only illustrated one form of such system embodying the present invention, in which rather specific circuit arrangements have been disclosed, it is desired to be understood that the particular embodiment of the invention illustrated has not been selected for 95 the purpose of showing the exact construction preferably employed in practicing the invention, nor has it been selected to show the scope of the invention, but it merely has been selected for the purpose of facilitating the disclosure of the invention; it is desired to be understood that various changes modifications and additions may be made to adapt the invention to the particular railway system to which the invention is to be applied, all without departing from the spirit or scope of the invention or the idea of means underlying the same except as demanded by the scope of the following claims. 105

What I claim as new is:—

1. In a train dispatching system of the selector type, the combination with a single line circuit extending along the railway track and connecting a large number of way stations and a dispatcher's office, code responsive means at each way station for rendering available a particular message circuit branch upon the reception of a particular code, and means controlled over such message circuit for again making such 115 branch unavailable. 120

2. In a train dispatching system of the selector type, the combination with a single line circuit extending along the railway track and connecting a large number of way 125 stations and a dispatcher's office, means responsive to a plurality of distinctive impulses transmitted in a distinctive order which when it responds makes available for use a particular message circuit branch, and 130

a relay controlled over such message circuit branch for again making said branch unavailable for use.

3. In a train dispatching system of the selector type, the combination with a single line circuit extending along the railway track and connecting a large number of way stations and a dispatcher's office, means responsive to a plurality of distinctive impulses transmitted in a distinctive order which when it responds makes available for use a particular message circuit branch, said message branch forming part of a message circuit including said single line circuit, control means and controllable means included in said message circuit, and other means for discontinuing said message circuit available for use and rendering said line circuit available for transmitting another code.
- 20 4. In a train dispatching system of the selector type, the combination with a single line circuit extending along the railway track and connecting a large number of way stations and a dispatcher's office, means responsive to a plurality of distinctive impulses transmitted in distinctive order which when it responds makes available for use a particular message circuit branch, said message branch forming part of a message circuit including said single line circuit, means controlled over said message circuit to inform the engineer of an approaching train how he is to move his train, and other means for discontinuing said message circuit for use and rendering said line circuit available for transmitting another code.
- 25 5. A train dispatching system comprising, a dispatcher's office, a plurality of way stations, a pair of wires connecting said dispatcher's office and said way stations, distinctive code transmitting means at said dispatcher's office, code responsive means at each way station each responsive to a particular code transmitted over said pair of wires from said dispatcher's office, and means controlled by said code transmitting means for at times allotting said pair of wires for the transmission of distinctive codes and at another time allotting said pair of wires for controlling a switch machine at the way station, said switch machine being controlled by the code responsive means located at such way station.
- 30 6. A train dispatching system comprising, a dispatcher's office, a plurality of way stations, a pair of wires connecting said dispatcher's office and said way stations, distinctive code transmitting means at said dispatcher's office, code responsive means at each way station each responsive to a particular code transmitted over said pair of wires from said dispatcher's office, and means controlled by said code transmitting means for at times allotting said pair of wires for the transmission of distinctive codes and at another time allotting said pair of wires for the transmission of distinctive codes and at

another time allotting said pair of wires for controlling a signal at the way station controlled by the code responsive means located at such way station.

7. A train dispatching system comprising, a dispatcher's office, a plurality of way stations, a pair of wires connecting said dispatcher's office and said way stations, distinctive code transmitting means at said dispatcher's office, code responsive means at each way station each responsive to a particular code transmitted over said pair of wires from said dispatcher's office, and means controlled by said code transmitting means for at times allotting said pair of wires for the transmission of distinctive codes and at another time allotting said pair of wires for controlling an indicator at the dispatcher's office in accordance with traffic conditions at the way station, said indication being controlled through a contact governed by a code responsive means located at such way station.

8. In a train dispatching system, a dispatcher's office, a plurality of way stations, a pair of wires connecting said dispatcher's office and said way stations, selector apparatus at said dispatcher's office and at said way stations for completing successive message circuits each including the same line wire by transmitting successive distinctive codes to said way stations, levers for controlling signals over said message circuits, and means for preventing a particular code being transmitted when the lever for controlling a traffic controlling device over the message circuit rendered available by such code is in a position to open such message circuit, whereby only those distinctive codes are transmitted which are necessary to establish the message circuits required at that particular time.

9. In a train dispatching system, a dispatcher's office, a plurality of way stations, a pair of wires connecting said dispatcher's office and said way stations, selector apparatus at said dispatcher's office and at said way stations for completing successive message circuits each including the same line wire by transmitting successive distinctive codes to said way stations, levers for controlling switch machines over said message circuits, and means for preventing a particular code from being transmitted when the lever for controlling a traffic controlling device over the message circuit rendered available by such code is in its circuit open position, whereby only those distinctive codes are transmitted which are necessary to establish the message circuits required at that particular time.

10. In a train dispatching system of the selector type, the combination with a single line circuit extending along the railway track and connecting a large number of way

stations and a dispatcher's office, code responsive means at each way station for rendering available a particular message circuit branch upon the reception of a particular code, a railway signal controlled over said message circuit, and means controlled over such message circuit for again making such branch unavailable.

11. A train dispatching system comprising, a dispatcher's office, a plurality of way stations, a pair of wires connecting said dispatcher's office and said way stations, distinctive code transmitting means at said dispatcher's office, code responsive means at each way station each responsive to a particular code transmitted over said pair of wires from said dispatcher's office, and means controlled by codes originating in said dispatcher's office for at times controlling a traffic controlling device located at a particular way station and at other times controlling an indicator in said office in accordance with traffic conditions at another way station over said pair of line wires.

25 In testimony whereof I affix my signature.

DISCLAIMER

1,824,117.—*Frederick W. Brixner, Rochester, N. Y.* TRAIN-DISPATCHING SYSTEM FOR RAILROADS. Patent dated September 22, 1931. Disclaimer filed February 16, 1934, by the assignee, *General Railway Signal Company*.

Hereby enters this disclaimer to claims 5, 6, 7, and 11 of said Letters Patent, which are in the following words, to wit:

“5. A train dispatching system comprising, a dispatcher's office, a plurality of way stations, a pair of wires connecting said dispatcher's office and said way stations, distinctive code transmitting means at said dispatcher's office, code responsive means at each way station each responsive to a particular code transmitted over said pair of wires from said dispatcher's office, and means controlled by said code transmitting means for at times allotting said pair of wires for the transmission of distinctive codes and at another time allotting said pair of wires for controlling a switch machine at the way station, said switch machine being controlled by the code responsive means located at such way station.

“6. A train dispatching system comprising, a dispatcher's office, a plurality of way stations, a pair of wires connecting said dispatcher's office and said way stations, distinctive code transmitting means at said dispatcher's office, code responsive means at each way station each responsive to a particular code transmitted over said pair of wires from said dispatcher's office, and means controlled by said code transmitting means for at times allotting said pair of wires for the transmission of distinctive codes and at another time allotting said pair of wires for controlling a signal at the way station controlled by the code responsive means located at such way station.

“7. A train dispatching system comprising, a dispatcher's office, a plurality of way stations, a pair of wires connecting said dispatcher's office and said way stations, distinctive code transmitting means at said dispatcher's office, code responsive means at each way station each responsive to a particular code transmitted over said pair of wires from said dispatcher's office, and means controlled by said code transmitting means for at times allotting said pair of wires for the transmission of distinctive codes and at another time allotting said pair of wires for controlling an indicator at the dispatcher's office in accordance with traffic conditions at the way station, said indication being controlled through a contact governed by a code responsive means located at such way station.”

“11. A train dispatching system comprising, a dispatcher's office, a plurality of way stations, a pair of wires connecting said dispatcher's office and said way stations, distinctive code transmitting means at said dispatcher's office, code responsive means at each way station each responsive to a particular code transmitted over said pair of wires from said dispatcher's office, and means controlled by codes originating in said dispatcher's office for at times controlling a traffic controlling device located at a particular way station and at other times controlling an indicator in said office in accordance with traffic conditions at another way station over said pair of line wires.”

[*Official Gazette March 13, 1934.*]

DISCLAIMER

1,824,117.—*Frederick W. Brixner*, Rochester, N. Y. TRAIN DISPATCHING SYSTEM FOR RAILROADS. Patent dated September 22, 1931. Disclaimer filed July 28, 1934, by the assignee, *General Railway Signal Company*.

Hereby disclaims from claim 2 any system of train dispatching in which the "means responsive to a plurality of distinctive impulses transmitted in a distinctive order" is responsive to a varying number of short impulses and a long impulse always transmitted in the same order of the short impulses before the long impulse.

[*Official Gazette August 21, 1934.*]
